UNITED STATES PATENT OFFICE.

MAURICE M. GOLDENSTEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,136,668.

Specification of Letters Patent. Patented Apr. 20, 1915.

Application filed October 10, 1913. Serial No. 794,415.

To all whom it may concern:

Be it known that I, MAURICE M. GOLDENSTEIN, a citizen of the United States, residing at Milwaukee, in the county of Milwaukee and State of Wisconsin, have invented new and useful Improvements in Motor-Controllers, of which the following is a full, clear, concise, and exact description, reference being had to the accompanying drawing, forming a part of this specification.

My invention relates to improvements in controllers for electric motors. It is particularly applicable to motor-operated printing presses but may be advantageously employed in other relations.

Heretofore it has been customary to provide for regulation of motor-driven printing presses by means of push-button controlled rheostats, the degree of regulation being determined by the length of time that the desired push button has been manually maintained in operative position. This system of control has been found to be highly desirable in connection with this class of machinery, among other reasons because it enables the press to be readily adjusted to the various different speeds required thereof for different purposes. However, in some instances, as for example, where the press is many times stopped or slowed down and then restored to the same speed, the necessity of manually holding the accelerating push-button has resulted in so great demand on the attendant's time and attention as to be objectionable.

My invention has among its objects to provide a controller having the advantageous features of the aforesaid controllers, and also means whereby the motor may at any time be accelerated to a predetermined speed by operation of a push button or other suitable switch without necessitating manual retention thereof.

A further object is to provide for variation of the aforesaid predetermined speed in a convenient and expeditious manner.

Various other objects and advantages of my invention will hereinafter appear.

For the purpose of more fully disclosing the nature and advantages of my invention I shall describe the embodiment thereof illustrated in the accompanying drawing, it being understood that my invention may be

embodied in other forms and employed in other relations.

The controller illustrated is particularly applicable to motor-driven printing presses. It is shown as controlling a motor 1 having an armature A and a shunt field winding F and comprises a main line switch 2, an electromagnetically controlled rheostat 3 and a control station 4. The switch 2 controls the continuity of the motor circuit while the rheostat 3 controls resistances R and R' in series with the motor armature. Both the main line switch and the rheostat are controllable at will from the control station 4.

The rheostat 3 is in general of a conventional type and comprises a contact carrying cross head 5 arranged between and movable over two series of contacts 6 and 7 connected to the resistances R and R' respectively. The cross head 5 is connected to the plunger of a solenoid 8 and is adapted to be raised thereby to normal position as illustrated. A switch 8a opened by the cross-head when in normal position deenergizes solenoid 8. The cross head descends by gravity to remove the resistances 6 and 7 from the motor circuit and thus accelerate the motor. The descent of the cross-head is controlled by a pawl 9 co-operating with a ratchet extension 10 of the lifting solenoid 8. The pawl 9 normally stands in engagement with the ratchet extension to support the cross head in normal position and is adapted to be withdrawn therefrom by a magnet 11 to release said cross-head. The ratchet is provided with a plurality of teeth whereby the cross-head in its descent may be checked in any one of a number of different positions to provide for operation of the motor at any one of a number of different speeds. While the rheostat is illustrated as controlling only an armature resistance for the motor it should be understood that it may also be employed to control additional resistances, if desired.

The control station 4 comprises normally open push-button switches 12 and 13, a switch 14, preferably a snap switch, and a switch 15 which may be of any preferred type. The switch 14 controls the main switch 2 to start and stop the motor at will. The push button switch 12 controls the magnet 11 of pawl 9 to release the cross-head 5 and functions to affect descent of the cross-

head to any predetermined position corresponding to the length of time which it is held depressed. The push button switch 13 controls the lifting solenoid 8 of the cross-head, and, like switch 12, the length of time which it is held depressed determines the degree of movement of the cross-head 5. The switch functions with auxiliary contacts associated with the rheostat for purposes hereinafter set forth.

The auxiliary contacts associated with the rheostat comprise a series of contact buttons 16, a contact strip 17 and a bridging contact 18 carried by the cross-head 5 and insulated therefrom. These contacts control a shunt around the push button switch 12 during a predetermined range of movement of the cross-head, for a purpose hereinafter set forth. The contacts 16 preferably correspond in number to the operative positions of the cross-head 5 and are provided with interchangeable connections whereby the duration of the shunt established thereby may be varied as desired. Reverting now to the switch 13, the same is included in the shunt just mentioned. In brief, the function of the shunt established by the contacts 16, 17 and 18 is to enable operation of the rheostat to any predetermined position by momentary operation of the push-button 12 while the switch 13 enables checking of the rheostat at will. The control afforded by the aforesaid means is of a most flexible and convenient character and will now be more specifically described.

Operation of the switch 13 to complete a circuit from line 1, by conductors 33 through said switch by conductors 34, through the operating winding of switch 12, whereby the conductors 33 to line 1. The current through switch 13, however, may be interrupted by the action of switch 12, the current may then be taken from line 1 by conductor 23 through resistance R, contact 16, and resistance R' by conductors 24, therethrough terminated at terminal X, by conductors 25, therethrough, with R and by conductors 26 to line 17. The circuit extends from line 17 to the conductors 20 through 29, via line 1, the conductor 20 to line 17, the conductor 27 to line 17. The action of this arrangement with all of the resistance included in the aforesaid circuit, whereby will operate to slow speed.

Push-button 12 when pressed closes a circuit from line 1, through switch 12, and is otherwise closed by conductors 33 through said switch 12, by conductors 30 through 31, conductors 31, 32, conductors 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 580, 581, 582, 583, 584, 585, 586, 587, 588, 589, 590, 591, 592, 593, 594, 595, 596, 597, 598, 599, 590, 591, 592, 593, 594, 595, 596, 597, 598, 599, 600, 601, 602, 603, 604, 605, 606, 607, 608, 609, 600, 601, 602, 603, 604, 605, 606, 607, 608, 609, 610, 611, 612, 613, 614, 615, 616, 617, 618, 619, 610, 611, 612, 613, 614, 615, 616, 617, 618, 619, 620, 621, 622, 623, 624, 625, 626, 627, 628, 629, 620, 621, 622, 623, 624, 625, 626, 627, 628, 629, 630, 631, 632, 633, 634, 635, 636, 637, 638, 639, 630, 631, 632, 633, 634, 635, 636, 637, 638, 639, 640, 641, 642, 643, 644, 645, 646, 647, 648, 649, 640, 641, 642, 643, 644, 645, 646, 647, 648, 649, 650, 651, 652, 653, 654, 655, 656, 657, 658, 659, 650, 651, 652, 653, 654, 655, 656, 657, 658, 659, 660, 661, 662, 663, 664, 665, 666, 667, 668, 669, 660, 661, 662, 663, 664, 665, 666, 667, 668, 669, 670, 671, 672, 673, 674, 675, 676, 677, 678, 679, 670, 671, 672, 673, 674, 675, 676, 677, 678, 679, 680, 681, 682, 683, 684, 685, 686, 687, 688, 689, 680, 681, 682, 683, 684, 685, 686, 687, 688, 689, 690, 691, 692, 693, 694, 695, 696, 697, 698, 699, 690, 691, 692, 693, 694, 695, 696, 697, 698, 699, 700, 701, 702, 703, 704, 705, 706, 707, 708, 709, 700, 701, 702, 703, 704, 705, 706, 707, 708, 709, 710, 711, 712, 713, 714, 715, 716, 717, 718, 719, 710, 711, 712, 713, 714, 715, 716, 717, 718, 719, 720, 721, 722, 723, 724, 725, 726, 727, 728, 729, 720, 721, 722, 723, 724, 725, 726, 727, 728, 729, 730, 731, 732, 733, 734, 735, 736, 737, 738, 739, 730, 731, 732, 733, 734, 735, 736, 737, 738, 739, 740, 741, 742, 743, 744, 745, 746, 747, 748, 749, 740, 741, 742, 743, 744, 745, 746, 747, 748, 749, 750, 751, 752, 753, 754, 755, 756, 757, 758, 759, 750, 751, 752, 753, 754, 755, 756, 757, 758, 759, 760, 761, 762, 763, 764, 765, 766, 767, 768, 769, 760, 761, 762, 763, 764, 765, 766, 767, 768, 769, 770, 771, 772, 773, 774, 775, 776, 777, 778, 779, 770, 771, 772, 773, 774, 775, 776, 777, 778, 779, 780, 781, 782, 783, 784, 785, 786, 787, 788, 789, 780, 781, 782, 783, 784, 785, 786, 787, 788, 789, 790, 791, 792, 793, 794, 795, 796, 797, 798, 799, 790, 791, 792, 793, 794, 795, 796, 797, 798, 799, 800, 801, 802, 803, 804, 805, 806, 807, 808, 809, 800, 801, 802, 803, 804, 805, 806, 807, 808, 809, 810, 811, 812, 813, 814, 815, 816, 817, 818, 819, 810, 811, 812, 813, 814, 815, 816, 817, 818, 819, 820, 821, 822, 823, 824, 825, 826, 827, 828, 829, 820, 821, 822, 823, 824, 825, 826, 827, 828, 829, 830, 831, 832, 833, 834, 835, 836, 837, 838, 839, 830, 831, 832, 833, 834, 835, 836, 837, 838, 839, 840, 841, 842, 843, 844, 845, 846, 847, 848, 849, 840, 841, 842, 843, 844, 845, 846, 847, 848, 849, 850, 851, 852, 853, 854, 855, 856, 857, 858, 859, 850, 851, 852, 853, 854, 855, 856, 857, 858, 859, 860, 861, 862, 863, 864, 865, 866, 867, 868, 869, 860, 861, 862, 863, 864, 865, 866, 867, 868, 869, 870, 871, 872, 873, 874, 875, 876, 877, 878, 879, 870, 871, 872, 873, 874, 875, 876, 877, 878, 879, 880, 881, 882, 883, 884, 885, 886, 887, 888, 889, 880, 881, 882, 883, 884, 885, 886, 887, 888, 889, 890, 891, 892, 893, 894, 895, 896, 897, 898, 899, 890, 891, 892, 893, 894, 895, 896, 897, 898, 899, 900, 901, 902, 903, 904, 905, 906, 907, 908, 909, 900, 901, 902, 903, 904, 905, 906, 907, 908, 909, 910, 911, 912, 913, 914, 915, 916, 917, 918, 919, 910, 911, 912, 913, 914, 915, 916, 917, 918, 919, 920, 921, 922, 923, 924, 925, 926, 927, 928, 929, 920, 921, 922, 923, 924, 925, 926, 927, 928, 929, 930, 931, 932, 933, 934, 935, 936, 937, 938, 939, 930, 931, 932, 933, 934, 935, 936, 937, 938, 939, 940, 941, 942, 943, 944, 945, 946, 947, 948, 949, 940, 941, 942, 943, 944, 945, 946, 947, 948, 949, 950, 951, 952, 953, 954, 955, 956, 957, 958, 959, 950, 951, 952, 953, 954, 955, 956, 957, 958, 959, 960, 961, 962, 963, 964, 965, 966, 967, 968, 969, 960, 961, 962, 963, 964, 965, 966, 967, 968, 969, 970, 971, 972, 973, 974, 975, 976, 977, 978, 979, 970, 971, 972, 973, 974, 975, 976, 977, 978, 979, 980, 981, 982, 983, 984, 985, 986, 987, 988, 989, 980, 981, 982, 983, 984, 985, 986, 987, 988, 989, 990, 991, 992, 993, 994, 995, 996, 997, 998, 999, 990, 991, 992, 993, 994, 995, 996, 997, 998, 999, 1000, 1001, 1002, 1003, 1004, 1005, 1006, 1007, 1008, 1009, 1000, 1001, 1002, 1003, 1004, 1005, 1006, 1007, 1008, 1009, 1010, 1011, 1012, 1013, 1014, 1015, 1016, 1017, 1018, 1019, 1010, 1011, 1012, 1013, 1014, 1015, 1016, 1017, 1018, 1019, 1020, 1021, 1022, 1023, 1024, 1025, 1026, 1027, 1028, 1029, 1020, 1021, 1022, 1023, 1024, 1025, 1026, 1027, 1028, 1029, 1030, 1031, 1032, 1033, 1034, 1035, 1036, 1037, 1038, 1039, 1030, 1031, 1032, 1033, 1034, 1035, 1036, 1037, 1038, 1039, 1040, 1041, 1042, 1043, 1044, 1045, 1046, 1047, 1048, 1049, 1040, 1041, 1042, 1043, 1044, 1045, 1046, 1047, 1048, 1049, 1050, 1051, 1052, 1053, 1054, 1055, 1056, 1057, 1058, 1059, 1050, 1051, 1052, 1053, 1054, 1055, 1056, 1057, 1058, 1059, 1060, 1061, 1062, 1063, 1064, 1065, 1066, 1067, 1068, 1069, 1060, 1061, 1062, 1063, 1064, 1065, 1066, 1067, 1068, 1069, 1070, 1071, 1072, 1073, 1074, 1075, 1076, 1077, 1078, 1079, 1070, 1071, 1072, 1073, 1074, 1075, 1076, 1077, 1078, 1079, 1080, 1081, 1082, 1083, 1084, 1085, 1086, 1087, 1088, 1089, 1080, 1081, 1082, 1083, 1084, 1085, 1086, 1087, 1088, 1089, 1090, 1091, 1092, 1093, 1094, 1095, 1096, 1097, 1098, 1099, 1090, 1091, 1092, 1093, 1094, 1095, 1096, 1097, 1098, 1099, 1100, 1101, 1102, 1103, 1104, 1105, 1106, 1107, 1108, 1109, 1100, 1101, 1102, 1103, 1104, 1105, 1106, 1107, 1108, 1109, 1110, 1111, 1112, 1113, 1114, 1115, 1116, 1117, 1118, 1119, 1110, 1111, 1112, 1113, 1114, 1115, 1116, 1117, 1118, 1119, 1120, 1121, 1122, 1123, 1124, 1125, 1126, 1127, 1128, 1129, 1120, 1121, 1122, 1123, 1124, 1125, 1126, 1127, 1128, 1129, 1130, 1131, 1132, 1133, 1134, 1135, 1136, 1137, 1138, 1139, 1130, 1131, 1132, 1133, 1134, 1135, 1136, 1137, 1138, 1139, 1140, 1141, 1142, 1143, 1144, 1145, 1146, 1147, 1148, 1149, 1140, 1141, 1142, 1143, 1144, 1145, 1146, 1147, 1148, 1149, 1150, 1151, 1152, 1153, 1154, 1155, 1156, 1157, 1158, 1159, 1150, 1151, 1152, 1153, 1154, 1155, 1156, 1157, 1158, 1159, 1160, 1161, 1162, 1163, 1164, 1165, 1166, 1167, 1168, 1169, 1160, 1161, 1162, 1163, 1164, 1165, 1166, 1167, 1168, 1169, 1170, 1171, 1172, 1173, 1174, 1175, 1176, 1177, 1178, 1179, 1170, 1171, 1172, 1173, 1174, 1175, 1176, 1177, 1178, 1179, 1180, 1181, 1182, 1183, 1184, 1185, 1186, 1187, 1188, 1189, 1180, 1181, 1182, 1183, 1184, 1185, 1186, 1187, 1188, 1189, 1190, 1191, 1192, 1193, 1194, 1195, 1196, 1197, 1198, 1199, 1190, 1191, 1192, 1193, 1194, 1195, 1196, 1197, 1198, 1199, 1200, 1201, 1202, 1203, 1204, 1205, 1206, 1207, 1208, 1209, 1200, 1201, 1202, 1203, 1204, 1205, 1206, 1207, 1208, 1209, 1210, 1211, 1212, 1213, 1214, 1215, 1216, 1217, 1218, 1219, 1210, 1211, 1212, 1213, 1214, 1215, 1216, 1217, 1218, 1219, 1220, 1221, 1222, 1223, 1224, 1225, 1226, 1227, 1228, 1229, 1220, 1221, 1222, 1223, 1224, 1225, 1226, 1227, 1228, 1229, 1230, 1231, 1232, 1233, 1234, 1235, 1236, 1237, 1238, 1239, 1230, 1231, 1232, 1233, 1234, 1235, 1236, 1237, 1238, 1239, 1240, 1241, 1242, 1243, 1244, 1245, 1246, 1247, 1248, 1249, 1240, 1241, 1242, 1243, 1244, 1245, 1246, 1247, 1248, 1249, 1250, 1251, 1252, 1253, 1254, 1255, 1256, 1257, 1258, 1259, 1250, 1251, 1252, 1253, 1254, 1255, 1256, 1257, 1258, 1259, 1260, 1261, 1262, 1263, 1264, 1265, 1266, 1267, 1268, 1269, 1260, 1261, 1262, 1263, 1264, 1265, 1266, 1267, 1268, 1269, 1270, 1271, 1272, 1273, 1274, 1275, 1276, 1277, 1278, 1279, 1270, 1271, 1272, 1273, 1274, 1275, 1276, 1277, 1278, 1279, 1280, 1281, 1282, 1283, 1284, 1285, 1286, 1287, 1288, 1289, 1280, 1281, 1282, 1283, 1284, 1285, 1286, 1287, 1288, 1289, 1290, 1291, 1292, 1293, 1294, 1295, 1296, 1297, 1298, 1299, 1290, 1291, 1292, 1293, 1294, 1295, 1296, 1297, 1298, 1299, 1300, 1301, 1302, 1303, 1304, 1305, 1306, 1307, 1308, 1309, 1300, 1301, 1302,

the manual retention of the switch 13 and accordingly the degree of elevation of the cross head is likewise dependent thereon. As soon as the push-button 13 is released the upward movement of the cross-head is checked and under these conditions if the cross-head is in a position to close the shunt around the push-button switch 12 the cross-head will immediately return to position X. 10 However, should it be desired to prevent this automatic return of the cross-head this may be readily accomplished by opening the switch 15 and thereby opening said shunt circuit.

15 In addition to the aforesaid means of effecting the elevation of the cross-head, means are illustrated to automatically raise the cross-head to normal position upon deenergization of main line switch 2. This means 20 includes auxiliary contacts 40 and 41 on said switch 2 and the auxiliary switch 8^a of the rheostat heretofore mentioned. When the main line switch is deenergized with the cross-head below normal position, circuit is 5 closed from line L by conductors 20, 35 and 42 through the auxiliary contacts 40 and 41 of switch 2, by conductor 36 through switch 8^a and thence through solenoid 8 to line L, as already traced. Completion of 30 this circuit energizes the solenoid to restore the cross-head 5 to normal position, whereupon switch 8^a is opened to interrupt said energizing circuit.

To summarize, the controller provides for 35 automatic acceleration to any one of a number of predetermined speeds at the same time permitting manual control to restrict or further increase acceleration and also permitting subsequent manual control to obtain 40 speed variations of different degrees either positive or negative and for either temporary or prolonged periods.

What I claim as new and desire to secure 45 by Letters Patent is:

1. The combination with an electromagnetically controlled rheostat, of means for effecting operation thereof at will, and means for maintaining the same in operation between certain positions independently of said former means, said latter means being controllable at will to arrest said rheostat in one or more intermediate positions.

2. The combination with an electromagnetically controlled rheostat, of manual control means for effecting operation thereof, said means when released tending to automatically arrest said rheostat and means for maintaining said rheostat in operation between certain positions independently of 50 said former means, said latter means being controllable at will to arrest said rheostat in one or more intermediate positions.

3. The combination with an electromagnetically controlled rheostat, of means adapted when said rheostat is set in opera-

tion to effect continuous movement thereof from one position to another and manual control means operable to set said rheostat in operation and arrest the same intermediate of the aforesaid positions.

4. The combination with an electromagnetically controlled rheostat, of means adapted when said rheostat is set in operation to effect continuous movement thereof between certain positions, and manual control means for effecting operation of said rheostat in opposite directions and for arresting the same upon movement in either direction in a position intermediate of the aforesaid positions.

5. The combination with an electromagnetically controlled rheostat, of manual means for effecting operation thereof but effective only during manual retention and means for maintaining said rheostat in operation independently of said former means through a definite range of movement and then automatically arresting the same.

6. The combination with an electromagnetically controlled rheostat, of manual means for effecting operation thereof but effective only during manual retention thereof and means for maintaining said rheostat in operation independently of said former means through a definite range of its movement and then automatically arresting the same, said second-mentioned means being controllable at will to arrest said rheostat within the aforesaid range of movement.

7. The combination with an electromagnetically controlled rheostat, of manual means for effecting operation thereof and for stopping the same at will in any one of a number of different positions and means adapted to automatically arrest said rheostat in any one of a number of different predetermined positions.

8. The combination with an electromagnetically controlled rheostat, of manual means for effecting operation thereof and for stopping the same at will in any one of a number of different positions and means adapted to automatically arrest said rheostat in a predetermined position, said first mentioned means being adapted to effect operation of said rheostat in opposite directions from the position in which it is automatically stopped.

9. The combination with an electromagnetically controlled rheostat, of manual means for effecting operation thereof and for stopping the same at will in any one of a number of different positions and means adapted to automatically arrest said rheostat in a predetermined position, said first-mentioned means being adapted to effect operation of said rheostat in opposite directions from the position in which it is automatically stopped and to varying degrees.

10. The combination with an electromagn-

- netically controlled rheostat, of means for automatically arresting the same in any one of a number of different predetermined positions and manual means for effecting operation of said rheostat in either direction and for arresting the same in any one of a number of different positions either before or after the same is automatically arrested.
11. The combination with an electromagnetically controlled rheostat, of circuit controlling means operable to effect operation thereof and upon release to arrest the same and automatically controlled connections for rendering the release of said switch ineffective to arrest said rheostat in its movement between certain positions.
12. The combination with an electromagnetically controlled rheostat, of circuit controlling means therefor manually operable to effect operation of said rheostat and upon release to arrest the same and automatic circuit controlling means for arresting said rheostat in any one of a number of different predetermined positions and for rendering the release of said former means ineffective to arrest said rheostat in its movement from another position to the aforesaid predetermined position.
13. The combination with an electromagnetically controlled rheostat, of circuit controlling means operable to effect operation of said rheostat in one direction and upon release to arrest the same and circuit connections controlled by said rheostat for rendering the release of said means ineffective to arrest the operation of said rheostat in its movement between certain positions.
14. The combination with an electromagnetically controlled rheostat, of circuit controlling means manually operable to effect operation of said rheostat and tending when released to arrest the same, automatically controlled connections for rendering the release of said former means ineffective to arrest said rheostat in its movement between certain positions and manual means controlling said connections to arrest said rheostat intermediate of the aforesaid positions.
15. In a motor controller, the combination with an electromagnetically controlled speed regulator of circuit controlling means manually operable to effect operation of said
- regulator and tending when released to arrest the same, automatically controlled connections for rendering the release of said former means ineffective to arrest said regulator in its movement between certain positions and manual means controlling said connections to arrest said regulator intermediate of the aforesaid positions upon movement of the same in either direction.
16. In a motor controller, the combination with an electromagnetically controlled speed regulator, of circuit controlling means for effecting operation thereof in either direction, said means being effective only during manual retention thereof and automatic circuit controlling means for maintaining said regulator in operation independently of said former means between certain positions thereof.
17. In a motor controller, the combination with an electromagnetically controlled speed regulator, of circuit controlling means for effecting operation thereof in either direction, said means being effective only during manual retention thereof and automatic circuit controlling means for maintaining said regulator in operation independently of said former means between certain positions thereof, and said first-mentioned means being adapted to arrest said regulator intermediate of the aforesaid positions.
18. In a motor controller, the combination with an electromagnetically controlled device for regulating the speed of the motor, of circuit controlling means for effecting operation thereof in either direction, said means being effective only during manual retention thereof and automatic circuit controlling means for maintaining said device in operation independently of said former means between certain positions thereof and said first-mentioned means being adapted to arrest said device intermediate of the aforesaid positions and to restore the same to such intermediate position after passing the same.
- In witness whereof, I have hereunto subscribed my name in the presence of two witnesses.
